UNITED STATES PATENT OFFICE.

REINHOLD D. SCHOENWETTER, OF BALTIMORE, MARYLAND, ASSIGNOR, BY MESNE ASSIGNMENTS, TO THE NATIONAL MANUFACTURING COMPANY, OF BALTIMORE, MARYLAND, A CORPORATION OF MARYLAND.

COATING MACHINE.

1,416,984.

Specification of Letters Patent. Patented May 23, 1922.

Original application filed May 17, 1917, Serial No. 169,248. Divided and this application filed July 2, 1919. Serial No. 308,134.

To all whom it may concern:

Be it known that I, REINHOLD D. SCHOENWETTER, a citizen of the United States, residing at Baltimore, in the State of Maryland, have invented certain new and useful Improvements in Coating Machines; and I do hereby declare the following to be a full, clear, and exact description of the invention, such as will enable others skilled in the art 10 to which it appertains to make and use the same.

My invention relates to coating machines.

This is a divisional application from my co-pending application Ser. #169248, filed 15 May 17, 1917, for cigar banding machine.

The object of my invention is to provide an improved wetting mechanism for cigar banding machines though it should be understood that I do not limit my invention to this 20 specific application, as the principles thereof may be applied to labeling and analogous machines generally.

More specifically considered, my present invention relates to improvements in band 25 wetting mechanisms for use with those cigar banding machines in which a supply of cigar bands, each having a dry gummed end, is carried in a magazine stacked one upon the other and delivered one at a time to a wetting mechanism and then to the band applying mechanism proper. In such machines, it is of great importance that the gummed portion of the band be so moistened that it will not be too wet or too dry when it reaches 30 the band applying mechanism and that the moisture applying means shall not remove the gum from the band.

In order to fully describe my said invention, reference will be had to the accompanying drawings, wherein:—

Fig. 1 is a fragmentary top plan view of my improved mechanism with parts omitted for the sake of clearness.

Fig. 2 is a vertical section, partly in elevation, of my improved mechanism.

Fig. 3 is a fragmentary elevation, partly in section, of the wetting mechanism.

Fig. 4 is a detail sectional view of the wetting mechanism, shown longitudinally.

Fig. 5 is a detail vertical section on the line 6—6 of Fig. 4.

In the machine, the cigar bands are carried stacked in any suitable magazine, not shown,

and the bands 11 are removed therefrom by suction, a suction head 35 being provided 55 rigidly mounted upon one end of a crooked metal tube 36, rigidly secured to a supporting frame 37, vertically slidable in guides 38 and adapted to receive vertical reciprocatory motion, for which purpose the said frame 60 37 is connected through a link 39 to a lever 40 carrying a roller 41 adapted to travel in an eccentric groove or slot 42 in one face of the disk 33. The lower end of the tube 36 is connected through a flexible tube 43 to the 65 forward end of one of the cylinders 44^a of a double air pump 44 driven from a disk 45 having an eccentric groove 46, in which travels a roller 47 carried by a lever 48, connected through a link 49 to the piston cross 70 head 50 of the air pump. The disk 45 is mounted upon a shaft 51 which receives its motion from power shaft 34 through a sprocket gearing 34^a, 52 and 53.

The bands are removed from the magazine 75 by the above described suction mechanism and are delivered to a conveyor which comprises a pair of metal belts 59 and 60, traveling respectively upon flanged rollers 61, 62, 63 and 64. The rollers 62 and 64 are provided with equally spaced peripheral pins 65 and 66 which are adapted to extend through equally spaced openings 67 and 68 in the respective belts and thereby impart travel thereto. The rollers 62 and 64 are 80 fast on the shaft 69 and are connected through gears 70 and 71 to a ratchet 72 85 mounted on a stud shaft 73.

This ratchet is adapted to receive motion from a pawl 74 carried by an arm 75 mounted 90 for rocking motion on shaft 73, which motion is imparted to said arm through a lever 76 connected thereto through a link 77, the lever 76 being integral with the collar 26^a, and the collar 26^a in turn being fast with the 95 rock shaft 27. Also fast on this shaft is an arm 28 and this arm receives rocking motion from the lever 30 which carries a roller 31 traveling in a cam slot 32 in one face of the disk 33 fast on the power shaft 34, hereinbefore described. Arm 28 is connected to the lever 30 by means of the link 29.

Fast on the conveyor belts 59 and 60, respectively, are a series of spring clips 78 and 79 spaced at regular intervals thereon in such 100 arrangement as to form pairs in which the

clips of the respective pairs lie exactly opposite each other and are in a line at right angles to the lengthwise direction of the bands. The function of these clips is to 5 move the bands one at a time from the suction head 35 and hold them in position on the conveyor belts until they are removed therefrom, as hereinafter described.

The wetting mechanism comprises, amongst 10 other parts, a trough or tank 80 in which is carried a supply of water 81 and into which is adapted to extend a roller 82 fast on a shaft 83, connected through the gearing 84, 85 and 86 to the shaft 69 so as to impart 15 to the roller 82 the same surface velocity as that to the conveyor belts 59 and 60. A presser roller 87 journaled in bearings 88 and 89 (see Fig. 4), vertically movable in an overhanging bracket 90, is normally held 20 in peripheral engagement with the roller 82 under the compression of springs 91 and 92, the tension of which may be regulated by screws 93 and 94. Rollers 82 and 87 are located at one side of the conveyor belt 60 25 (at the right in Fig. 1) at such distance that the gummed end of each cigar band carried by the conveyor belts will pass between said rollers.

The tank 80 is mounted for horizontal 30 movement in two guide supports 95 and 96 and is adjustable horizontally by a screw 97. This arrangement affords a means for adjusting the wetting rollers horizontally.

The mechanism for removing the bands 35 from the conveyor belts comprises, amongst other parts, a hinged or pivotally mounted stripper 98 consisting of a yoke having arms 99 and 100 carrying on their outer ends rollers 101 and 102, respectively, which 40 travel upon plates 103 and 104, rigidly secured to the machine frame and having their forward ends bent downward to form inclined planes 105 and 106 on which the rollers 101 and 102 travel as hereinafter 45 more particularly described. The arms 99 and 101 carry pins 107 and 108 which, when said arms travel forward, engage a band on the conveyor belt and carry it forward until its forward edge engages with two stop pins 50 109 and 110 fast on plates 103 and 104, respectively. When the bands are brought to this position, a suction head 111 rises into engagement therewith, draws the engaged band 17 downward and delivers it to the 55 banding unit 112 indicated by dotted lines in Fig. 2. The banding unit per se, however, does not constitute any part of the present invention and for that reason need not here be described in detail.

60 The stripper or yoke 98 is hinged to the upper end of a rocker arm 113 and the rollers 101 and 102 are held in engagement with the plates 103 and 104 under the tension of a spring 114. The rocker arm 113 receives 65 motion from a lever 115 connected to it

through a link 116, the lever 115 receiving its motion from a disk 117 having an eccentric or cam groove 118 in which travels a roller 119 carried by the lever 115. The disk 117 is fast on a shaft 120 driven by the 70 sprocket gearing 53—121.

The suction head 111 is fast upon the upper end of a metal tube 122 fast to a slide 123 mounted for vertical reciprocating motion in the guides 124 and connected through a link 75 125 to a lever 126 having a roller 127 which travels in an eccentric groove 128 in one face of the disk 117. The lower end of the suction tube 122 connects through a flexible tube 129 to one end of the pump cylinder 44^b. 80 The suction heads 35 and 111 are similar, except in that the head 111 has but one suction opening 130 through its top, whereas the head 35 has two such openings.

For the purpose of forming an upper stop 85 or anvil for the bands when engaged by the suction head 111 in rising, there is provided a plate 131 rigidly secured to the machine frame and extending forwardly between the conveyor belts. The operation of my improved coating machine is as follows:—

It will be assumed that the shaft 34 is in rotation and continues so throughout a complete cycle of the machine. By means of the movement imparting mechanism described, 95 the continued rotation of the shaft 34 results in the step-by-step travel of the conveyor belts 59 and 60; an up and down motion of the suction heads 35 and 111; a forward and backward movement of the stripper device 98, and reciprocating motion of the pump pistons.

At the beginning of the cycle, the tube 36 rises, thereby causing the suction head 35 to travel upward and bringing the top surface of the suction head into engagement with the lowermost band of the stack of bands in the magazine, not shown. This movement completely seals the suction head and at this instant the pistons of the pumps 110 44^a and 44^b start on their outward strokes, 105 thereby creating suction against the band in engagement with the suction head and holding it firmly thereon. After pausing with the suction head in the position described, 115 tube 36 travels downward, causing the suction head 35 to descend and carry the band held thereon by suction with it. The suction head 35 continues its travel downward until it reaches the position indicated in 120 Fig. 2 with the band held just above the conveyor belts, the said band being still held on the suction head by suction. The conveyor belts now advance one step under the action of the ratchet and pawl mechanism 125 72—77 hereinbefore described, whereupon a pair of the clips 78 and 79 engage the cigar band held by the suction head 35, remove it from said suction head and carry it to the 130 next stopping position (A). After the clips

engage the band, as described, the pump pistons reverse their stroke, thereby releasing the suction applied to the head 35.

On the next step of the conveyor belts, the 5 band is brought to position B when it stops again, and on the next succeeding step, passes between the wetting rollers and on to the next stopping position C, and is carried along step by step, through the action of the 10 pawl 74 on the ratchet 72 to the position D, then the arm 113 rocks forward, whereupon the pins 107 and 108 engage the band, push it forward out of its retaining clips and position its forward edge against the pins 109 15 and 110, thus correcting any displacement which the band may have undergone in transit and insuring its correct positioning on the suction head 111. When the arm 113 reaches the limit of its forward stroke, it 20 pauses for an instant. At this time, the suction head 111 moves up and engages the band held between the pins 107—108 and 109—110, and the instant this takes place the piston of the pump cylinder 44^b starts on 25 its suction stroke, thereby creating a suction on the band in engagement with the suction head 111. Suction head 111 then travels downward, carrying the band with it, and after it has reached the limit of its down- 30 ward travel, the piston of the pump cylinder 44^b reverses its stroke and relieves the suction on the band, whereupon it becomes free. The instant the suction head 111 starts down with a band, the arm 113 rocks back to the 35 position shown in Fig. 2 and the belt conveyor advances another step.

It will be noted that the wetting of the gummed end of the band takes place far in advance of its delivery to the band applying 40 mechanism. This gives ample time for the proper softening of the gum. It has also been found that soapstone is the best material of which to make the roller 82, such material having relatively little friction. The 45 best material for the roller 87 is rubber, as this will yield when the bands pass between the two rollers. When these rollers travel at the same surface velocity as the band passing between them, removal of the gum in the 50 wetting process is practically eliminated.

It should be understood that, while the expression "cigar bands" is used in the accompanying claims, this is intended to include other strips or sheets of flexible material, the said expression being used merely for convenience.

I claim:—

1. The combination with a tank, of a pair 55 of rollers one of which is adapted to extend into liquid in said tank, and the other constructed of yieldable material and pressed upon said first-named roller, and a belt conveyor having band holding means adapted to pass a portion of said bands between said 60 rollers.

2. The combination with a tank, of a pair of rollers one of which is adapted to extend into liquid in said tank, a belt conveyor having band holding means adapted to cause said bands to pass between said rollers, and means to drive said roller in said tank and said conveyor at the same surface speed. 70

3. In a coating machine the combination with a tank, of a wetting roller for coating bands, the peripheral surface of which is 75 composed of material having relatively little friction with said bands, said roller being mounted with respect to said tank to extend thereto, a presser roller pressing upon said wetting roller, and a conveyor 80 having band holding means adapted to pass a portion of the bands thereon between said rollers.

4. In a coating machine the combination with a tank, of a wetting roller for coating 85 bands, the peripheral surface of which is composed of material having relatively little friction with said bands, said roller being mounted with respect to said tank to extend thereto, a presser roller pressing 90 upon said wetting roller, and a belt conveyor having band holding means adapted to pass a portion of the bands thereon between said rollers.

5. The combination with a wetting roller, 95 the peripheral surface of which is composed of material having relatively little friction, means to wet said roller, a presser roller pressing upon said wetting roller, and a conveyor having band holding means and 100 adapted to pass a portion of said bands held thereon between said rollers.

6. The combination with a wetting roller, means to wet said roller, a presser roller, 105 constructed of yieldable material, pressing upon said wetting roller, and a conveyor having band holding means and adapted to pass a portion of said bands held thereon between said rollers.

7. The combination with a wetting roller, 110 means to wet said roller, a presser roller constructed of yieldable material pressing upon said wetting roller, and a belt conveyor having band holding means and adapted to pass a portion of said bands held thereon 115 between said rollers.

8. The combination with a tank, of a wetting roller, the peripheral surface of which is composed of soapstone, said roller being mounted with respect to said tank to extend thereto, a presser roller co-acting with said wetting roller, and a conveyor having band holding means adapted to cause the bands thereon to pass between said rollers. 120

9. The combination with a wetting roller, 125 the peripheral surface of which is composed of soapstone, means to wet said roller, a presser roller adapted to co-act with said wetting roller, and a conveyor having band holding means and adapted to cause said 130

bands held thereon to pass between said rollers.

10. The combination with a wetting roller, of means to wet said roller, a roller pressing 5 against said wetting roller, a belt conveyor having band holding means for passing a portion of a band held thereby between said rollers, and means to drive said conveyor and wetting roller at substantially the same surface speed.

11. The combination with a wetting roller, of means to wet said roller, a presser roller adapted to co-act with said wetting roller, a belt conveyor having band holding means, 15 and means positively acting step by step to drive said conveyor and wetting roller at substantially the same surface speed.

12. In a coating machine the combination with a roller for coating bands, the peripheral surface of which is of material having a low coefficient of friction with said bands, of means to wet said roller, a presser roller adapted to co-act with said wetting roller and having a peripheral surface of material 25 having a different coefficient of friction with said bands from the first mentioned roller,

and band conveying mechanism adapted to cause a gummed portion of the bands to pass between said rollers.

13. In a coating machine the combination 30 with a roller for coating bands, the peripheral surface of which is of material having a low coefficient of friction with said bands, of means to wet said roller, a presser roller adapted to co-act with said wetting roller 35 and having a peripheral surface of material having a relatively high coefficient of friction with said bands, and band conveying mechanism adapted to cause a gummed portion of the bands to pass between said rollers. 40

14. The combination with a roller, the peripheral surface of which is composed of soapstone, of means to wet said roller, a presser roller adapted to co-act with said wetting roller and having a peripheral surface composed of soft rubber, and band conveying mechanism adapted to cause a gummed portion of the bands to pass between 45 said rollers.

In testimony whereof, I affix my signature.

REINHOLD D. SCHOENWETTER.
